UNITED STATES PATENT OFFICE.

SAMUEL C. RODESS, OF NEW YORK, N. Y.

SIGNAL BELL.

Application filed May 12, 1922. Serial No. 560,284.

To all whom it may concern:

Be it known that I, SAMUEL C. RODESS, a citizen of the United States, and resident of the borough of Manhattan, city of New York, in the county of New York and State of New York, have invented certain new and useful Improvements in Signal Bells, of which the following is a specification.

My invention relates to improvements in the class of signal bells adapted to be operated to sound signals by the pressure of gases from the cylinder of an internal combustion engine, and has reference to the class of signal bells set forth in my application filed November 10, 1921, Serial No. 514,236.

One of the objects of my present invention is to enable the clapper when actuated by pressure from an engine cylinder to strike the bell and rebound therefrom quickly so as not to interfere with the tone of the bell.

Another object of my invention is to provide means to automatically cut off the operating pressure from the movable member that actuates the clapper so as to limit the time of the pressure against such member during its operating stroke.

My invention also comprises novel details of improvement that will be more fully hereinafter set forth and then pointed out in the claims.

Reference is to be had to the accompanying drawings, forming part hereof, wherein

Figures 1 and 2 are vertical sections through a signal bell embodying my improvements, showing parts in different positions, taken substantially on line 1—1 in Fig. 3;

Fig. 3 is a side view looking from the left in Fig. 1; the bell being omitted;

Fig. 4 is an enlarged detail face view, partly in section, of my improved pressure controlling means;

Fig. 5 is a diagrammatic view illustrating my improvements in position on a portion of an automobile.

Fig. 6 is a side view of a valve to control pressure for the signal bell;

Figure 6^a is a section on line 6^a—6^a in Figure 6.

Fig. 7 is a vertical section through Fig. 6;

Figs. 8 and 9 are details illustrating means to connect the signal bell with a support;

Fig. 10 is a partly sectional detail view illustrating modified means to operate the clapper;

Fig. 11 is a detail view illustrating another modification to operate the clapper; Fig. 12 is a vertical section of Fig. 11; Fig. 13 is a side view looking from the left in Fig. 11, the bell being omitted, and Fig. 14 is a section on line 14—14 in Fig. 11.

Similar numerals of reference indicate corresponding parts in the several views: 65

The bell 1 is shown provided with a support 2 shown in tubular or cylindrical form. The bell may be attached to the support 2 by any suitable means, such as by the threaded piece or screw 3. Reciprocatively within the bore 2^a of support 2 is a movable member 4 adapted to operate a clapper-actuator 5 that is pivotally carried upon support 2.

The clapper 6 is pivotally carried within the bell upon support 2 by means of pivot 7 or pin 7, shown extending through the clapper and lug 8 on said support, which lug extends into opening 6^a in the clapper, (Figs. 1, 2, 3 and 10). The clapper is shown provided with an adjustable striker 6^a, shown 80 in the form of a bolt, passing through the lower end of the clapper, in Figs. 1, 2, 3, and retained in set position by a nut 6^b, whereby the striker may be set in position on the clapper to produce the best striking results 85

against the bell. If desired, the striker may be omitted as shown in Figs. 10 to 13. A spring 9 between the upper end of the clapper and support 2 tends normally to aid in withdrawing the clapper from the bell and to retain the clapper away from the bell as in Fig. 1, although the clapper operates also under the influence of gravity. Cooperative means are provided between the movable member 4 and the actuator 5 for rocking the latter according to the reciprocations of said member, for which purpose I have shown the member 4 provided with rack-like teeth 4^a and the actuator 5 provided with teeth 5^a in mesh with teeth 4^a, which teeth 5^a extend through an opening 2^b in the wall of support 2 to engage the teeth 4^a. In the form shown in Figs. 1, 2 and 3, the actuator 5 has a projecting portion in cam-like form, indicated at 5^b, having correspondingly 90 curved cam-like surfaces 5^c on opposite sides

to operate the clapper, Fig. 2. The clapper is shown provided with an abutment 10, shown in the form of an anti-friction roll on a pin 10^a in the clapper, said roll being 100 located in opening 6^c of the clapper, whereby as actuator 5 is rocked it will engage said

95

100

105

110

abutment on both the downward and upward strokes of the projection 5^b to cause the clapper to strike the bell. As projection 5^b will quickly pass abutment 10 the clapper will be released from the bell for quick return therefrom, to prevent resistance to the clear ringing of the bell. In Fig. 10 the projection 5^b is pivotally connected with a link 11 that is hung on pin 10^a on the clapper and pivoted to projection 5^b by pin 12. When the actuator 5 is rocked by member 4, the connections or linkage 5^b, 12, 11 and 10^a, will cause the clapper to be quickly rocked to engage and retreat from the bell.

15 The bore 2^a of support 2 is to be supplied with gas or air under pressure on one stroke and influenced by release of the pressure or by exhaust on the next stroke, and so on alternately, to reciprocate member 4. Said bore 2^a may be connected with a cylinder of a gas engine, indicated at A, by any suitable means, either by direct connection through a hole in the cylinder, or by connection with a priming spark plug mounted 25 on the cylinder, or by means of a tube 14 interposed between the cylinder and support 2. To control the effective pressure and exhaust in bore 2^a of support 2, I provide the following means:—the reciprocative member 4 has a stem 15 depending therefrom and which may be detachably connected to member 4 by screw threads 16 and locking nut 17 (Figs. 1, 2 and 4). The stem 15 travels freely through an apertured valve member or disk 18 secured within bore 2^a so that gases may pass through the bore of said disk 18 freely around stem 15 (Figs. 1 and 2). Disk 18 has seats 18^a, 18^b, on opposite sides, to cooperate with valves 19, 20, 30 slidably freely on stem 15 on opposite sides of disk 18 to respectively cooperate with seats 18^a, 18^b. Stem 15 is provided with stops or shoulders 15^a, 15^b, to limit the movement of valves 19, 20, on said stem (Fig. 4). 35 A spring 21 on stem 15 normally pushes valve 19 toward seat 15^a and a spring 22 on said stem bearing against a stop 23 on said stem normally pushes valve 20 toward shoulder 15^b. By the means described the valves 40 19 and 20 may alternately bear against opposite sides of disk 18 and may float with stem 15 free from disk 18 for a distance of travel of member 4.

45 A fitting 25 is provided with threads 25^a engaging corresponding threads in bore 2^a of member 2, the inner end of member 25 being adapted to engage valve disk 18 to retain it against a stop shoulder 26 in bore 2^a, (Figs. 1 and 2). The member 25 is 50 adapted to be connected with a support and is shown provided with an external threaded portion at 25^b, adapted to receive a nut 27. The fitting 25 may be provided with threads 55 to receive a union fitting 28 for connection with tube 14. The threads 25^b may be

screwed into a support, such as the engine casing A (Fig. 8), and nut 27 may be set against said support to retain the support 2 in the desired adjusted position. The threads 25^b may be screwed into a retaining plate 29 and held in an adjusted position by nut 27, which plate 29 may be attached to any desired support, indicated at B. The construction is such, also, that the threaded part 25^b of fitting 25, or the threaded part 70 of support 2 at 46, (Figs. 10, 11, 12), may be clamped by a yoke-like bracket 30 and retained by nut 27, which bracket may be clamped on the filler neck 31 of an automobile radiator 32 (Fig. 5).

80 Suitable means may be provided to control pressure and exhaust in bore 2^a of support 2. In Figs. 5, 6 and 7, I have illustrated valve means comprising a casing 32 having a threaded projection 33 to receive union 34 (Fig. 5) to connect tube 14 with the valve casing. A valve 35 controls the flow of gas through bores 32^a, 32^b of casing 32 to and from tube 14. The stem 36 of valve 35 is shown normally pushed by spring 37 to seat valve 35 and a lever 38 pivoted at 39 on casing 32 is adapted to push stem 36 to unseat valve 35. Lever 38 may be operated by suitable means, such as by a wire connection 40 extending to a lever 41 attached by a bracket 42 to the steering post 43 of the automobile, or in any other position convenient to the operator. The casing 32 has a threaded portion 32^c and a nut *a*, which threaded portion may be screwed into a hole in the engine cylinder to receive fluid pressure therefrom, the nut *a* enabling the casing 32 to be set and retained in any convenient position for the pull-connection 40.

100 When the engine is operating and valve 35 is opened the pressure and exhaust produced by the engine will be effective through tube 14 to bore 2^a of support 2. The pressure will pass stem 15 through disk 18 and operate against member 4 to cause it to rise (in Fig. 1), whereby actuator 5 will rock against abutment 10 to cause clapper 6 to strike the bell, and said actuator will pass quickly from said abutment during the continued stroke of member 4 to permit the clapper to fall away from the bell; on the reverse stroke of member 4 actuator 5 will be rocked reversely to pass abutment 10 to cause the clapper to again strike, and so on alternately, whereby rapid operation of the clapper may be effected, since the projection 5^b will quickly slide past abutment 10 on each stroke. When member 4 has risen on the pressure stroke part of its limit of travel the valve 20 will engage seat 18^b to shut off flow of fluid against member 4 and the momentum of said member will cause it to continue a short distance against the resistance of spring 22 interposed under pres-

sure between valves 20 and 23 and then stop. For the next stroke suction or exhaust in the lower part of bore 2^a as well as the effect of gravity, will cause member 4 to descend 6 and its valve 20 will pass from seat 18^b, and toward the limit of such stroke of member 4 the valve 19 will engage seat 18^a to shut off the effect of the exhaust in bore 2^a against member 4, and the momentum of 10 said member will be checked by spring 21 interposed between member 4 and valve 19 and the member will stop. The effect of the operation described is that member 4 is subjected to pressure and exhaust during a portion 15 of its strokes only while the remainder of its strokes is cushioned by springs 21, 22, alternately, to prevent injury to the parts by rapid reciprocations to which member 4 may be subjected.

20 In the forms shown in Figs. 11 to 14, I provide two clappers 6 hung upon pin 7, with means to operate them alternately toward and from the bell. In this form the actuator 5 has lateral extensions or shaft 25 portions 5^a, journaled in bearings in lugs 2^a on casing 2, which shaft portions have eccentrically disposed crank pins 5^e, shown out of register axially with each other (Fig. 14), so as to act in the nature of double-throw cranks. The crank pins 5^e connect with links 5^f that are pivotally connected with the respective clappers 6 by means of pins 5^g on the clappers (Fig. 14). The arrangement is such that as actuator 5 is rotated back and forth by the reciprocations of member 4, the crank pins 5^e will be correspondingly rocked whereby the links 5^f will cause alternate swinging of the clappers 6 to strike the bell alternately.

40 In Fig. 12 the movable member 4 is shown opposed by springs 44, 45, on opposite sides of said member within bore 2^a of support 2, whereby the movements of member 4 will be restrained.

45 Instead of connecting support 2 to a tube 14, said support may be connected directly to the engine cylinder, as in the place of valve 32, in Fig. 5, by means of threads 46 on said support. The support may be set 50 in the desired position for convenience in operating lever 47 and retained by nut 27. The bore 2^a of support 2 leads through the lower end of the latter and has a valve seat 48 to cooperate with the valve 49 having a stem 50, that passes through bore 2^a and through a bore 4^b in member 4, said stem being in position to be engaged by lever 47.

55 A spring 51 engaging a stop or pin 52 on stem 50 and engaging also a nut-like member 53 screwed into the upper end of support 2 serves normally to seat valve 49 against seat 48. The member 53 may clamp the bell against the end of support 2, as indicated in Fig. 12.

60 My improvements are particularly adapted for use as signal bells for automobiles, motor boats and the like having internal combustion engines, since when such an engine is operating and its pressure and exhaust is in bore 2^a of support 2 the member 4 will be reciprocated so long as valve 35 or valve 49 is retained open. When such valve is closed the clapper will not operate. My invention is particularly useful on fire engines and ambulances, where loud ringing 65 alarms are desirable owing to the conditions under which such vehicles are usually operated.

70 My invention is not limited to the details of construction set forth since the same may be varied, within the scope of the appended claims, without departing from the spirit of my invention.

75 Having now described my invention, what I claim is:

80 1. A signal bell comprising a support, a movable member, a bell, a clapper, a rotative actuator for the clapper provided with teeth, said member having teeth engaging the first named teeth, and means to admit 85 fluid pressure and exhaust to the support to actuate said member.

85 2. A signal bell comprising a support, a movable member, a bell, a clapper, an actuator pivotally carried by said support and provided with a cam-like projection to actuate the clapper, teeth cooperative between 90 said actuator and member for operating the former by the latter, and means to admit fluid pressure and exhaust to the support 95 to actuate said member.

100 3. A signal bell comprising a support, having a bore provided with an opening, a bell, a clapper, an actuator pivotally carried by said support and having a projection provided with cam-like faces on opposite sides, said clapper having means to be engaged by said projection, a movable member having teeth, said actuator having teeth operative in said opening and cooperative 105 with the teeth of said member for rocking the actuator by the member and means to admit fluid pressure and exhaust to the support 110 to actuate said member.

115 4. A signal bell comprising a support, a bell, a clapper, a fluid pressure operated movable member carried by the support, cooperative devices between said member and clapper to cause said member to actuate the clapper, said member and support being provided with cooperative means to cut off pressure against the member during its strokes.

120 5. A signal bell comprising a support, a bell, a clapper, a fluid pressure operated movable member carried by the support and cooperative devices between said member and clapper to cause said member to actuate the clapper, said member and support being pro-

- vided with cooperative means to cut off pressure and exhaust against said member before the termination of its strokes.
6. A signal bell comprising a support, having a passage for fluid pressure, a bell, a clapper, a movable member carried by the support, means to cause said member to actuate the clapper, said member being provided with a stem having spaced valves, said support having seats for said valves in said passage, said valves being so spaced as to engage said seats alternately, and means to admit fluid pressure and exhaust to said passage.
15. 7. A signal bell comprising a support, having a passage for fluid pressure, a bell, a clapper, a movable member carried by the support, means to cause said member to actuate the clapper, a stem carried by said member having spaced valves, seats for said valves in said passage, and springs cooperative with said valves to permit continued movement of said member when the valves are on their respective seats, and means to admit fluid pressure and exhaust to said passage.
8. A signal bell comprising a support, having a passage for fluid pressure, a bell, a clapper, a movable member carried by the support, means to cause said member to actuate the clapper, said member being provided with a stem, valves slidable upon said stem and spaced apart in said passage, and seats carried by said support for said valves, said stem being operative freely through said seats, and means to admit fluid pressure and exhaust to said passage.
9. A signal bell comprising a support, having a passage for fluid pressure, a bell, a clapper, a movable member carried by the support, means to cause said member to actuate the clapper, said member being provided with a stem, valves slidable upon said stem and spaced apart in said passage, seats carried by said support for said valves, said stem being operative freely through said seats, and springs interposed respectively between one of said valves and said member and between the other valve and a stop on said member, said stem having spaced stops for said valves, and means to admit fluid pressure and exhaust to said passage.
10. A signal bell comprising a support, a bell, a clapper pivotally carried by said support between the latter and said bell, a movable member reciprocative within said support, actuating means for the clapper pivotally carried by the support to be rocked by said member, the clapper having an abutment to be engaged by said actuating means during its rocking movements, and means to control admission of fluid pressure to said support.
11. The combination of a support having a bore, a bell, a member movable within said bore, a clapper, means to cause the member to operate the clapper, a tube communicating with said bore, a casing connected to said tube, said casing having valve means to control the flow of fluid pressure and exhaust within said tube, and means to support said valve casing upon an internal combustion engine in communication with its cylinder to cause pressure and exhaust between said bore and to actuate said member.
12. The combination of a support having a bore, a tube communicating with said bore, a member slidable in said bore, a bell, a clapper, means to operate the clapper by said member, a casing having means to connect it with the cylinder of an internal combustion engine, said casing having a bore communicating with said tube, and valve means to control the flow of pressure and exhaust from and to said cylinder through said tube.

SAMUEL C. RODESS.
